UNITED STATES PATENT OFFICE.

ALBERT MALSIN, OF NEW YORK, N. Y., ASSIGNOR TO LANE BRYANT, INC., OF NEW YORK, N. Y., A CORPORATION OF NEW YORK.

LADY'S GARMENT.

1,293,152.

Specification of Letters Patent. Patented Feb. 4, 1919.

Application filed July 9, 1915. Serial No. 38,846.

To all whom it may concern:

Be it known that I, ALBERT MALSIN, a citizen of the United States of America, residing at New York, in the county of New York and State of New York, have invented certain new and useful Improvements in Ladies' Garments, of which the following is a specification.

The present invention relates to ladies' garments and particularly to the type of garment known to the trade as divided skirt or pantaloons.

The object of the invention is to produce a garment of that type which will give great comfort and freedom of movement of the limbs and which in order to avoid the objectionable vulgar appearance will substantially have the form of a skirt.

To accomplish my object the garment is composed of an outer part adapted to constitute the skirt and which is made up of two separate pieces, each folded into the shape of an oval and both connected only at their upper edges or at the waistband portion, and an inner part made of two or more pieces cut and sewed together in the form of pantaloons, but which differs from ordinary pantaloons in that they are open at their outer sides and have no waist portion.

The longitudinal edges along the open sides are sewed to the parts forming the skirt and constitute trunks for the limbs. In order to provide for great freedom of movement to the limbs and to conceal the pantaloon-shaped inner part and the crotches thereof, the pieces forming the skirt are so cut as to gradually widen toward the bottom and are plaited all around or only in front and back, and the plaits are so arranged that the central plaits or those located at the points of connection of the two pieces will almost touch one another, thereby concealing the crotches of the pantaloon-shaped inner parts. In walking the skirt portions will part from one another and in order to allow the wearer to prevent such parting, if so desired, suitable fastening means are concealed below the plaits, whereby the two pieces of the skirt portion of the garment may be fastened together.

My invention will be more fully understood by reference to the accompanying drawing, which forms part of this specification, and in which similar reference char-

acters denote corresponding parts, Figure 1 being an elevation of my new garment; Fig. 2 a cross section on line 2—2 of Fig. 1; Fig. 3 a cross section on line 3—3 of Fig. 1; Fig. 4 a longitudinal section on line 4—4 of Fig. 2; Fig. 5 an elevation of a modified structure; Fig. 6 a cross section on line 6—6 of Fig. 5, and Fig. 7 a cross section on line 7—7 of Fig. 5.

Referring to the drawing, it will be seen that the garment consists of two parts, an outer part A and an inner part B. The outer part is adapted to constitute the skirt and is composed of two pieces *a*, *a* each of which is folded into an oval (Fig. 2). The two pieces are sewed together only at their upper edges or at the waist band *w*, but are loose throughout the rest of the length of the garment, as at *a*^a, Figs. 1—5. The two pieces are each cut so as to be narrower at the waistband and widening toward the bottom and each of the pieces is formed with longitudinal flaring plaits *a*^b. The object of the plaits is first to provide for greater freedom of movement to the limbs of the wearer and secondly to conceal the real nature of the garment. The inner parts B is adapted to constitute pantaloons and is composed of two or more pieces *b*, *b* cut and sewed together in the form of pantaloons, forming the crotch *b*^a, but differing from real pantaloons in that the outer sides thereof are open, as at *b*^b. The longitudinal edges *b*^c along the open sides are sewed to the respective pieces *a* of the skirt, so that trunks *c*, *c* for the limbs of the wearer are formed. The plaitings are so arranged that those in front and back which are located in the center almost touch one another, as at *d*, and thus overlap the crotch of the pantaloons and conceal the inner part B.

Instead of the plaitings *a*^b the outer parts *a*, *a* may have folds *a*^c formed by turning their longitudinal edges inwardly, as in Figs. 6 and 7, and the pantaloon-shaped inner part B may have its longitudinal edges *b*^c at the open sides sewed to said folds, as at *b*^a (Fig. 5). The outer parts *a*, *a* will at their juncture overlap and thus conceal the crotch.

In order to allow the wearer, if she so desires, to connect the two parts of the skirt, so as to prevent the parting thereof while walking, I provide a buttonholed flap or tab

f and button *g* which I secure below the central plaits, as in Figs. 1-3, or to the folds *a*^c, as in Figs. 5 and 7. Instead, however, any other suitable fastening means may be 5 provided and concealed behind the plaits to allow of the two skirt portions being temporarily connected together.

In the modification according to Fig. 7 10 the garment is shown as capable of opening at the back. The inner pantaloон-shaped part B is divided on the central line, as at *b*^e, and there may be suitable closing means. Likewise the outer parts while connected in front are disconnected at the back and have 15 suitable closing means.

What I claim and desire to secure by Letters Patent is:

20 A lady's bifurcated skirt formed of two separate outer pieces constituting the visible portions of the garment united only at their

upper edges or waist portions, the lines of separation between these two pieces being from the waist portion downward and at the front and rear of the garment respectively, and two inner portions united together to form a crotch and each united along its front and back edges with one of the outer skirt pieces by substantially vertical seams that are located a short distance back from the edges of the vertical lines of separation between the outer pieces, the said inner pieces of the garment being without a distinct waist portion individual to the inner pieces of the garment.

25 In testimony whereof I affix my signature 30 in presence of two witnesses.

ALBERT MALSIN.

Witnesses:

HENRY HIRSCH,
MAX BERMAN.
